FIG. 3

FIG. 1 is a fragmentary schematic perspective view of the floor covering of my new designs;

FIG. 2 is a fragmentary side elevational view thereof; and

FIG. 3 is a fragmentary planar view of the floor covering showing my new design as it appears in use.

The characteristic feature of my design resides in the combination on a floor covering of the type disclosed of a series of parallel, folded felt strips secured in the center of their longer axis to a backing sheet, the sides of each strip being slotted so as to form relatively wide upstanding fringed rows each alternate strip being superposed by a narrower, more closely fringed strip, all as shown.

I claim:

The ornamental design for a floor covering or the like, as shown and described.
